(57) **CLAIM**

The ornamental design for a mobile power multifunction pen, as shown and described.

DESCRIPTION

FIG. 1 is a front view of a mobile power multifunction pen.

FIG. 2 is a back view thereof;

FIG. 3 is a left view thereof;

FIG. 4 is a right view thereof;

FIG. 5 is a perspective view thereof;

FIG. 6 is a top view thereof;

FIG. 7 is a bottom view thereof;

FIG. 8 is an exploded perspective view of first embodiment thereof;

FIG. 9 is an exploded perspective view of second embodiment thereof; and,

FIG. 10 is an exploded perspective view of third embodiment thereof.

1 Claim, 10 Drawing Sheets
